(57) **CLAIM**

We claim the ornamental design for a display screen or portion thereof with graphical user interface, as shown and described.

DESCRIPTION

The FIGURE is a front view of a display screen or portion thereof with graphical user interface, showing the new design.

The outer broken lines show the display screen or portion thereof and form no part of the claimed design. All other broken lines show portions of the graphical user interface and form no part of the claimed design.

1 Claim, 1 Drawing Sheet
